RADIUS TRUING ATTACHMENT

Andrew J. Graf, Norwood, Ohio, assignor to Cincinnati Grinders Incorporated, Cincinnati, Ohio, a corporation of Ohio

Application January 25, 1940, Serial No. 315,475

11 Claims. (Cl. 125—11)

This invention relates to the grinding art and more particularly to truing mechanism for grinding wheels.

One of the objects of this invention is to provide improved means for truing a formed surface on the periphery of a grinding wheel.

Another object of this invention is to provide an improved radius truing attachment for grinding machines.

Other objects and advantages of the present invention should be readily apparent by reference to the following specification, considered in conjunction with the accompanying drawings forming a part thereof and it is to be understood that any modifications may be made in the exact structural details there shown and described, within the scope of the appended claims, without departing from or exceeding the spirit of the invention.

Referring to the drawings in which like reference numerals indicate like or similar parts:

Figure 1 is an elevational view in cross section showing the mechanism of this invention.

Figure 2 is a section on the line 2—2 of Figure 1.

Figure 3 is a section on line 3—3 of Figure 1.

Figure 4 is a section on the line 4—4 of Figure 1.

Figure 5 is a detailed view as viewed on the line 5—5 of Figure 1.

Figure 6 is a section on the line 6—6 of Figure 5.

Figure 7 is a detail view on the line 7—7 of Figure 2.

This invention deals with a truing mechanism which is so designed that it is adaptable to be mounted on the guard which surrounds the grinding wheel in such a manner as to protect the operator in case of wheel breakage and incidentally to confine the coolant spray which is usually applied to the wheel during a grinding operation. Thus, the mechanism is always in position for utilization at any time without interference in any way with the work or fixtures utilized in connection with the work.

In Figure 1 of the drawings the reference numeral 10 indicates a conventional guard which surrounds a grinding wheel 11. The guard may be supported in any conventional manner on a fixed part of the machine, but since this forms no part of the present invention such support is not shown. The truing mechanism constituting this invention is adapted to true the periphery of the grinding wheel to a semi-circle 55

in cross section and is adjustable for variations in wheel width, as well as for wheel wear.

The truing mechanism comprises a tubular housing 12 which is attached to the guard in such manner as to provide for lateral adjustment with respect to the plane of rotation of the grinding wheel. The housing has a bore 13 whose axis lies in a radial plane of the wheel for slidably receiving a stud 14 attached to and supporting a yoke 15. In order to prevent any rotary movement of the yoke about its axis, a key 16 is provided between the stud and the housing. The yoke supports a diamond carrier 17 which is supported for rotation on the yoke about axis 18, and the carrier supports a diamond or truing tool 19 which has a truing point 20 that lies on the axis 21 which constitutes the axis of movement of the stud.

The intersection 22 of axes 18 and 21 represents the center of rotation of the truing point. It will now be evident that when the stud is moved axially that it will cause the truing point to move along the axis 21 and since this axis is a prolongation of the radius 23 of the grinding wheel, the truing point when rotated about the center 22 will move in a radial plane of the grinding wheel and thus provide a true arcuate or convex surface on the periphery of the wheel.

The stud 14 is shifted by a feed screw 24 which is anchored against axial movement at 25 in the housing and is threaded through a nut 26 mounted in the end of a bore 27 formed in the end of the stud. The bore 27 is elongated beyond the inner end of the nut to provide clearance for the screw. An operating gear 28 is keyed to the end of the screw and intermeshes with a second gear 29 fixed to the end of an operating shaft 30. A manually rotatable hand wheel 31 is secured to the end of the shaft 30 and is provided with graduations 32 which register with a fixed reference mark 33 scribed on the end of an arm 34 attached to the end of a housing 35. The arm is clamped against rotation to the housing by a clamping screw 36 but by loosening the clamping screw, the arm 33 may be adjusted about the axis of the shaft 30 to position the zero reference mark 33 relative to any graduation mark on the hand wheel to suit the convenience of the operator and to assist in determining the lengths of movement of the truing tool.

Thus rotation of the hand wheel 31 determines the amount of feeding movement to be imparted to the truing tool in a direction toward

or from the center of rotation of the grinding wheel.

One end of the yoke carries a housing 37 for enclosing the operating mechanism for effecting rotation of the carrier 17 about the axis 18. The carrier 17 is integral with the lower end of a shaft 38 which has a tapered bearing 39 by which it is held against axial movement by anti-friction thrust bearings 40. A worm wheel 41 is fixed to the upper end of the shaft and intermeshes with a worm 42 which is adapted to be rotated by a hand wheel 43. It will be noted that the worm and worm wheel form a reduction unit between the hand wheel and the carrier whereby a slow accurate rotation may be imparted to the truing tool, and in addition, since the worm and worm wheel are self-locking, the carrier 17 will be held against rotation in any position that it happens to stop. The end of the yoke 15 which supports housing 37 has a reduced portion 44 which passes through an aperture 45 formed in the guard 10 and it will be noted that since the yoke 15 is movable with the stud 14 in one plane and also laterally movable with the housing 12 in a second plane at right angles to the first, the aperture 45 must be made of sufficient dimensions to take care of both of these movements. Therefore, it is necessary to provide a large cover plate 46. Means are provided for clamping the cover plate to the guard in spite of the two directions of movement of the plate and this means comprises a clamping bolt 47 which, as shown in Figure 6, passes through a hole 48 in the guard 10, the hole being elongated as shown in Figure 5 to take care of one direction of movement while the bolt passes through a second hole 49 in the plate 46, which is elongated as shown in Figure 5 in a direction perpendicular to the long axis of the hole 48, to take care of the second direction of movement.

The square head 50 on one end of the bolt is guided by a strip 51 attached to the underside of the guard and this holds the bolt against rotation when the clamping nut 52 threaded on the other end of the bolt is rotated.

The amount of rotation of the carrier 17 is limited to 180 degrees and this limiting means is shown in Figure 3 of the drawings. The shaft 38 is provided with a radial pin 53 which engages the end of a set screw 54 for limiting the rotation in one direction, while the end of a set screw 55 limits the rotation in the other direction. These set screws are threaded in the yoke 15 and are clamped in adjusted position by clamping screws 56.

Various widths of grinding wheels may be applied to the end of the grinding wheel spindle 57 shown in Figure 2 and such spindles usually have a fixed flange 58 against which one face of the grinding wheel is placed and then a second flange is mounted on the end of the spindle and clamped against the opposite face of the grinding wheel. Thus, the position of the center of the face of the grinding wheel will vary in accordance with the width of the wheel. It is necessary, of course, that the center of rotation of the truing tool lie in the plane which passes through the center of the face of the grinding wheel. It is, therefore, necessary to provide for lateral adjustment of the housing 12 relative to the guard 10 in order that the plane of movement of the feed screw and the center of rotation of the carrier all lie in the central plane of the grinding wheel.

This is accomplished by providing six clamping screws 59 which, as shown in Figure 1, are

threaded into the guard and as shown in Figure 2 pass through elongated holes 60 formed in the flange 61 of the housing 12. When the screws 59 are loosened, a pair of adjusting screws 62 are rotated in one direction to effect adjustment of the housing to the right as viewed in Figure 2, while a second pair of set screws 63 are rotated to effect adjustments to the left. To assist in locating the housing in accordance with the width of the wheel, suitable graduations 64 are applied to the flange 61 for cooperation with a fixed reference mark 65 carried by the guard 10 to indicate the position of the housing for each wheel width. When a change in wheel width is made, adjustment must also be made in the radius of rotation of the truing point since this radius is always equal to one-half of the width of the wheel. To this end the holder 19 for the truing point 20 is supported in a bore 66 in the carrier 17 and held against rotation by a pin 67 which rides in a groove 68 formed longitudinally of the holder. The holder 19 is shown in Figure 4 in its maximum outward position as respects the axis of rotation 22 and inward movement is effected by rotating a nut 69 which is threaded on the reduced threaded end 70 of the holder 19.

The nut 69 has an annular flange 71 and by means of this flange the nut 69 is clamped against axial movement between a shoulder 72 on the carrier 17 and a plate 73 which is fastened to the carrier by screws 74. An operating collar 75 is secured to the end of the nut by a set screw 76 and this collar carries graduations 77 which cooperate with a zero mark 78 on the fixed member 73 to show the effective radius of the truing point. To increase the range of adjustment a second holder may be substituted for the holder 19 which is of greater length so that the effective radius may be graduated down to zero.

Since the radius adjusting mechanism for the truing tool is supported between the guard and the grinding wheel and therefore inaccessible, a removable cover plate 79, Figure 7, is slidably mounted between guides 80 on the guard, and when the cover plate is removed by knobs 81, an opening 82 in the guard is uncovered providing ready access to the mechanism.

There has thus been provided an improved radius truing attachment for a grinding wheel which may be mounted on the wheel guard or other suitable support, and which provides adjustment for variation in wheel width and in which the controls for the two functions of oscillating the truing tool and feeding it toward the wheel may be easily carried out by controls which are adjacent to one another.

What is claimed is:

1. In a truing mechanism for a grinding wheel, the combination with a guard for said wheel, of a housing mounted on said guard, a support member slidably mounted in said housing and guided for movement toward and from the axis of said wheel, a truing element pivotally supported by said member, means for adjusting the housing parallel to the axis of said wheel to position the pivotal axis of said truing element in the central plane of said wheel, and cooperating graduation marks carried by the housing and the guard for indicating this position in accordance with the width of the grinding wheel.

2. In a truing mechanism for a grinding wheel, the combination with a guard for said wheel, of a tubular housing mounted on said guard with its axis lying in a radial plane of said wheel, a yoke mounted within said guard having a stud pro-

jecting through the guard and guided in said tubular housing for movement parallel to the axis thereof, a carrier pivotally mounted in the ends of said yoke, a truing point mounted on the carrier, the pivotal axis of the carrier intersecting the axis of the tubular housing, an extension on said yoke projecting through the guard at a point remote from said housing, and means mounted on said extension exterior of the guard for rotating said carrier to cause the truing point to produce an arcuate surface on the periphery of the wheel.

3. In a truing mechanism for a grinding wheel, the combination with a guard for said wheel, of a tubular housing mounted on said guard with its axis lying in a radial plane of said wheel, a yoke mounted within said guard having a stud projecting through the guard and guided in said tubular housing for movement parallel to the axis thereof, a carrier pivotally mounted in the ends of said yoke, a truing point mounted on the carrier, the pivotal axis of the carrier intersecting the axis of the tubular housing, an extension on said yoke projecting through the guard at a point remote from said housing, means mounted on the guard and engaging said extension exterior of the guard for rotating said carrier to cause the truing point to produce an arcuate surface on the periphery of the wheel, and mechanism mounted on the housing for adjusting said yoke to move the truing point toward the wheel.

4. In a truing mechanism for a grinding wheel, the combination with a guard for said wheel, of a tubular housing mounted on said guard with its axis lying in a radial plane of said wheel, a yoke mounted within said guard having means projecting through the guard and guided in said tubular housing, a carrier pivotally mounted in the ends of said yoke, a truing point mounted on the carrier, the pivotal axis of the carrier intersecting the axis of the tubular housing at a point within the grinding wheel, an extension on said yoke projecting through the guard at a point remote from said housing, actuating means mounted on said extension exterior of the guard and connections between said means and the carrier for oscillating the latter to produce an arcuate surface on the periphery of the grinding wheel.

5. In a truing mechanism for a grinding wheel, the combination with a guard for said wheel, of a tubular housing mounted on said guard with its axis lying in a radial plane of said wheel, a yoke mounted within said guard and guided in said housing for movement in said radial plane, a carrier pivotally mounted in the ends of said yoke, a truing point mounted on the carrier, the pivotal axis of the carrier intersecting the axis of the tubular housing within the grinding wheel, an extension on said yoke projecting through the guard at a point remote from said housing, a hand wheel mounted on said extension exterior of the guard and operatively connected for rotation of the carrier, mechanism mounted on the housing for adjusting said yoke to move the truing point toward the grinding wheel, a hand wheel operatively connected to said mechanism, and means for supporting said last-named hand wheel adjacent the first-named hand wheel, whereby said hand wheels are nested for convenience of the operator.

6. In a truing mechanism for a grinding wheel, the combination with a guard for said wheel, of a housing for supporting said mechanism, means to attach said housing to the guard, truing tool

supporting means within the guard and having means supported and guided in said housing for producing radial movement of said supporting means toward and from the grinding wheel, a feed screw for effecting said feeding movement, a hand wheel, reduction gearing connecting the hand wheel to the screw, a support for the hand wheel, an arm attached to said support and terminating adjacent the periphery of said hand wheel for carrying a reference mark, micrometer graduations on the hand wheel cooperating with said reference mark to indicate the amount of movement imparted to the truing point, and means to adjust said arm relative to said support to position the reference mark adjacent any graduation on said hand wheel.

7. In a truing mechanism for a grinding wheel, the combination with a guard for said wheel having a pair of apertures formed therein, a yoke mounted within the guard having portions projecting through the respective apertures, a housing member adjustably mounted on the guard in circumscribing relation to one of the apertures and receiving one of the projections on the yoke, means carried by said housing for effecting axial adjustment of the projection and thus of the yoke, an auxiliary housing carried by the other projection of the yoke and disposed in overlying relation to the guard adjacent the other aperture therein, a truing tool carrier oscillatably mounted on the yoke within the guard, and means carried by the auxiliary housing exteriorly of the guard for effecting swinging movement of the carrier.

8. In a truing mechanism for a grinding wheel, the combination with a guard for said wheel having a pair of apertures formed therein, a yoke mounted within the guard having portions projecting through the respective apertures, a housing member adjustably mounted on the guard in circumscribing relation to one of the apertures and receiving one of the projections on the yoke, means carried by said housing for effecting axial adjustment of the projection and thus of the yoke, an auxiliary housing carried by the other projection of the yoke and disposed in overlying relation to the guard adjacent the other aperture therein, a truing tool carrier oscillatably mounted on the yoke within the guard, means carried by the auxiliary housing exteriorly of the guard for effecting swinging movement of the carrier, and means for securing the auxiliary housing to the guard to prevent oscillation of the yoke.

9. In a mechanism of the character described, the combination with a grinding wheel and a guard surrounding the wheel, of means for effecting a truing of the wheel within the guard including an oscillatable truing tool carrier, a yoke pivotally supporting the carrier having a pair of projections, a support mounted on one of said projections exteriorly of the guard, means for effecting relative adjustment of the support and projection to vary the position of the yoke within the guard in a direction toward and from the wheel, means adjustably securing the support to the guard whereby unitary lateral adjustment of the yoke and support may be effected with respect to the guard, the guard having an aperture formed therein to receive the other projection on the yoke, and means for securing said projection in adjusted position with respect to the guard to prevent tilting of the device.

10. In a mechanism of the character described, the combination with a grinding wheel and a

guard surrounding the wheel, of means for effecting a truing of the wheel within the guard including an oscillatable truing tool carrier, a yoke pivotally supporting the carrier having a pair of projections, a support mounted on one of said projections exteriorly of the guard, means for effecting relative adjustment of the support and projection to vary the position of the yoke within the guard in a direction toward and from the wheel, means adjustably securing the support to the guard whereby unitary lateral adjustment of the yoke and support may be effected with respect to the guard, the guard having an aperture formed therein to receive the other projection on the yoke, and means for securing said projection in adjusted position with respect to the guard to prevent tilting of the device, said securing means including an auxiliary housing disposed exteriorly of the guard and actuating means for the truing tool carried by the housing whereby the same may be rigidly supported on the guard.

11. In a mechanism of the character described, the combination with a grinding wheel and a guard surrounding the wheel, of means for effecting a truing of the wheel within the guard including an oscillatable truing tool carrier, a

yoke pivotally supporting the carrier having a pair of projections, a support mounted on one of said projections exteriorly of the guard, means for effecting relative adjustment of the support and projection to vary the position of the yoke within the guard in a direction toward and from the wheel, means adjustably securing the support to the guard whereby unitary lateral adjustment of the yoke and support may be effected with respect to the guard, the guard having an aperture formed therein to receive the other projection on the yoke, means for securing said projection in adjusted position with respect to the guard to prevent tilting of the device, said securing means including an auxiliary housing disposed exteriorly of the guard and actuating means for the truing tool carried by the housing whereby the same may be rigidly supported on the guard, an actuating portion on the carrier extending exteriorly of the guard by way of the projection on the yoke, and driving connections between the actuating means on the auxiliary support and said projection for effecting truing oscillation of the carrier.
